FINGER RING

William Park Hickman, Bridgeville, Pa., assignor of one-half to Russell C. Johnson, Mariemont, Ohio

Application January 18, 1952, Serial No. 18,109

Term of patent 14 years

(Cl. D45—10)

To all whom it may concern:

Be it known that I, William Park Hickman, a citizen of the United States, residing at R. D. No. 3, Bridgeville, Allegheny County, State of Pennsylvania, have invented a new, original, and ornamental Design for a Finger Ring, of which the following is a specification, reference being had to the accompanying drawings, forming a part thereof.

In the drawings:

Fig. 1 is a view in perspective of the top and one side of the finger ring showing my new design;

Fig. 2 is a view in perspective of the top and opposite side of the ring; and

Figs. 3 and 4 are views in side elevation of opposite sides of the ring, respectively.

I claim:

The ornamental design for a finger ring, as shown.

WILLIAM PARK HICKMAN.
